To all whom it may concern:

Be it known that I, Charles R. Kovar, a citizen of the United States, residing at 102-32 Park Lane South, Richmond Hill, Long Island, in the city of New York, county of Queens, and State of New York, have invented a new, original, and ornamental Design for a Glove, of which the following is a specification, reference being had to the accompanying drawing, forming part thereof.

Figures 1 and 2 are respectively a back view and a front view of a glove embodying my new design.

The entire glove is of ribbed fabric, the texture of which is shown in the drawing. A mock seam extends longitudinally of the back of the glove as shown in Figure 1, and a strap of fabric corresponding to that of the glove extends around the wrist portion, one end of the strap being spiralled into a button, as shown in Figure 1.

I claim:

The ornamental design for a glove, as shown and described.
